ELECTRIC PHOTOMETER

Daniel E. Christopher, Chicago, Ill.

Application May 21, 1937, Serial No. 143,997

3 Claims. (Cl. 88—23)

This invention relates to an improved electric photometer and has, for one of its principal objects, the provision of an instrument for measuring low light intensities over small areas and which is particularly adaptable for use in the photographic industry.

One of the principal objects of this invention is to provide a photometer which operates on the principle of comparing a known light value with an unknown light value and can be used to advantage in the process of timing exposures for photographic prints.

Another important object of the invention is the provision of an electric photometer which can be of a relatively simple and economical construction but which will be sufficiently accurate for practically all purposes for which such devices are ordinarily used.

A further object is to provide, in connection with a photometer of this type, a scale wherein relative multiples of time or any other desired factor may be readily and accurately determined.

Other and further important objects of the invention will be apparent from the disclosures in the accompanying drawing and following specification.

The invention, in a preferred form, is shown in the drawing and hereinafter more fully described.

30 In the drawing:

Figure 1 is a top plan view of the improved electric photometer of this invention, illustrating a preferred embodiment thereof.

Figure 2 is a sectional view taken on the line 35 A—A of Figure 1.

Figure 3 is a front elevation of the device shown in Figure 1.

Figure 4 is a horizontal section taken on the line B—B of Figure 3, parts being broken away.

Figure 5 is an enlarged section on the line C—C of Figure 1.

Figure 6 is a similar section on the line D—D of Figure 1.

Figure 7 is a top plan view, showing a modified form of the invention.

Figure 8 is a vertical section on the line E—E of Figure 7.

Figure 9 illustrates another modification.

As shown in the drawing:

50 The reference numeral 10 indicates generally the casing of the improved electric photometer of this invention, the same comprising essentially a light-tight box provided on its top with a rotatable knob 10a. This knob surmounts a scale 11 which itself is rotatable with respect to the casing 10 and which can be composed of any suitable material.

As illustrated, the scale is graduated for an immediate time indication, namely, seconds and 55 minutes, and in a logarithmic relationship, start-

ing from an indicated exposure of one second and up to a time of from nine to ten minutes. The use of such a rotatable logarithmic scale renders an accurate multiplication of the time values 5 relatively simple and easy, as a movement of the scale with regard to the arrow indicated at 14 permits multiplication by geometric addition of this logarithmic scale with a similar logarithmic scale (to the same base) of the factors employed. 10

As best shown in Figure 2, the casing 10 encloses a source of light 17, and the knob 10a is mounted on a post or shaft 19 rotatable in the casing and extending almost to the bottom thereof. At the lower end of this shaft 19 is fixed a 15 filter 18 which is made of any translucent material and comprises a series of areas graduated from light to dense as best indicated in Figure 4. The areas need not be defined by lines but may gradually merge into each other starting with a 20 space which is perfectly translucent and terminating in a space which is quite opaque, this being indicated by the variable spacing of the lines on the filter 18 as shown in Figure 4. This filter is arranged on the shaft 19 so that its original 25 position will correspond with the original setting position of the scale 11.

Light from the source 17 passes through the filter 18 onto a strip or pane of glass 12 as best shown in Figures 2 and 4, that portion of the glass not covered by the filter 18 being protected 30 by a shielding ledge or the like 20.

The slide of glass 12 is backed by an opaque white surface or coating 13 (Figure 2) which reflects the light which is passed through the filter 18 into the glass, and this accordingly illuminates field 22 at the forward edge of the glass in accordance with the known phenomenon that some of the light rays entering a sheet or pane of glass will be reflected back and forth from the inner faces of the surfaces and will accordingly 35 travel throughout the entire extent of the sheet making objects or markings anywhere on the surface more visible by indirect illumination. The forward edge of the glass slide 12 projects slightly beyond the casing 10 and is, in turn, 40 inclosed in a housing 30 forming an extension of the bottom of the casing 10.

The light of unknown intensity falls on the field 26 which reflects all light except that coming 45 through the slide 12 and illuminating the field 50 outlined by the opening 25. This light, of course, originates at the source 17 and is passed through the filter 18 onto, into and throughout the slide 12. By regulating the intensity of the light source either directly or by means of a filter such as 55 that shown at 18, the light intensity of the central field 25 may be varied; thereby the intensity of the illumination of the field 25 may be made to match that of the field 26, at which point the two fields appear as one. For any other unknown 60

light value, a different known value must be applied to make these fields match in intensity, and this explanation, of course, is applicable to the matching of the light fields 22 and 23.

5 By projecting the unknown light upon one field and the known light upon another in close proximity thereto and regulating the intensity of the latter until its reflection equals in intensity that of the unknown light, relative light values may 10 accordingly be determined over a broad range, and by providing a suitable scale the relative light values can be compared with a standard of measurement whereby desired readings may be immediately and directly made.

15 These two varying fields 23 and 26 are simple uncoated or uncovered portions of the surfaces of the slide 12 and are provided so that the device may be equally adaptable to the measurement of direct light as in contact printing of photographs and also to the measurement of reflected light as in projection printing.

In measuring direct light, the opening 21 is placed over the area to be measured, and the intensity of field 22 is controlled by manipulating 25 the knob 10a until the reflected light equals the intensity of the direct light whereupon the previously visible spot outlined by the opening 23 formed in the opaque white coating 13 disappears.

In measuring reflected light, the opening 24 is 30 placed under the area to be measured, and the light on the field 22 is controlled until the intensities of fields 22 and 26 are equal. Such 35 equalization of the light intensities, or, in other words, the illumination of the visible spots by control of the light intensity resulting from rotation of the knob 10a will immediately indicate to the operator the time in minutes or seconds required for the exposure of a negative or the like for proper photographic printing or development.

40 The density of the areas of the variable filter 18 are controlled so that the scale readings progress as the logarithms of the relative light values indicated. In other words, the relative light values are directly proportional to the time of exposure and may be substituted. A rotation and 45 subsequent setting of the scale 11 to a position so that any known paper speed factor coincides with the arrow 14 will immediately indicate a reading for a light value which will be the time required 50 for proper exposure of a particular paper. This direct multiplication is quite a convenience in handling photographic paper and other factors.

In Figures 7 and 8 are illustrated a slightly different means for varying the intensity of the known light.

55 Here a casing 42 is provided having a slot 46 in its top in which is slidably mounted a control knob or the like 44 which carries a source of light 45, the source of light being inside the casing.

60 At the bottom of the casing is provided a glass slide 43 similar to the slide 12, and the remainder of the apparatus is substantially the same as that shown in Figures 5 and 6.

The knob 44 is provided with a pointer which 65 moves over a scale 48 which may be graduated into any desired time periods.

In Figure 9, the casing 50 has mounted in its top a rotatable resistance knob 51 which controls a rheostat or variable resistance 47 whereby the intensity of the light source 52 is regulated, this, in turn, operating directly in conjunction with a glass slide or the like 53. A circular logarithmic scale similar to the scale 11 may be employed in this connection.

It will be seen that herein is provided a simple yet effective electric photometer which will be especially convenient and adaptable for photographic and similar work and which is so simple in operation that unusually accurate results can be immediately obtained by relatively unskilled persons.

5 Another distinct advantage of this device lies in the ability of the operator to accurately measure either direct or reflected light at substantially exactly a desired point or over very small areas, and directly on and closely adjacent to a designated surface. Errors are accordingly reduced to a minimum.

10 I am aware that many changes may be made 15 and numerous details of construction varied throughout a wide range without departing from the principles of this invention, and I, therefore, do not purpose limiting the patent granted hereon otherwise than as necessitated by the prior art. 20

I claim as my invention:

1. A light meter, comprising a light-tight casing, a source of light therein, a pane of glass in the bottom of the casing, one end of said glass pane extending beyond the casing, an opaque 25 coating on the projecting portion of the glass, said coating having an opening therein through which light in the glass is visible, means for varying the amount of light falling on the glass pane, said means comprising a translucent filter of 30 varying density, means for rotating said filter between the source of light and the glass pane, said means comprising a shaft extending through the box cover, an operating knob on the upper end of the shaft, and a logarithmic scale graduated 35 in time periods on the box cover beneath the knob, said scale being rotatable about the shaft and with respect to an indicated point on the box cover.

2. A photometer, comprising a casing, a source 40 of light in the casing, a pane of glass in the bottom of the casing, means for varying the amount of light falling on the glass, said glass pane projecting beyond the casing, a double cover for the projecting end, openings in the cover through 45 which the glass is exposed, opaque coatings on those portions of the glass beneath the openings, said coatings being cut away to provide small holes in approximately the center of the casing openings, one of said openings exposing the top 50 of the glass only while the other opening exposes both faces of the glass, the opaque coating and central hole being on the bottom surface of the glass in said last-named instance.

3. A photometer, comprising a light-tight casing, a source of light therein, a comparison field in the casing, said comparison field including a translucent spot surrounded by a reflecting area, means for varying the amount of light falling on the translucent spot, said means including a manually operated rotatable knob, and a logarithmic scale associated with the knob, said scale being itself rotatable about the same central point as the knob and adapted for adjustment for the speed of various types of photographic printing paper whereby a preliminary setting of the logarithmic scale in accordance with the paper used, and a later adjustment of the knob to vary the amount of light falling on the translucent spot will automatically indicate the time of exposure for the paper.

DANIEL E. CHRISTOPHER.
